ELECTRICAL POTENTIOMETER

George T. Brent, Clearwater, Fla., assignor to International Resistance Company, Philadelphia, Pa.

Filed May 21, 1963, Ser. No. 74,987

Term of patent 14 years

(Cl. D26—1)

The figure of the drawing is a perspective view of the electrical potentiometer of the present invention showing a unique design of the dial; the sides of the potentiometer not shown are flat and unornamented.

I claim:

The ornamental design for an electrical potentiometer, as shown and described.
